UNITED STATES PATENT OFFICE.

ROBERT S. GOURLAY, OF TORONTO, ONTARIO, CANADA, ASSIGNOR TO THE WILCOX & WHITE COMPANY, OF MERIDEN, CONNECTICUT, A CORPORATION OF CONNECTICUT.

TRACKER-BOARD.

No. 909,082.

Specification of Letters Patent.

Patented Jan. 5, 1909.

Application filed June 29, 1908. Serial No. 440,818.

To all whom it may concern:

Be it known that I, ROBERT S. GOURLAY, a subject of the King of Great Britain, residing at Toronto, Canada, have invented 5 certain new and useful Improvements in Tracker-Boards, of which the following is a full, clear, and exact description.

My invention relates to certain new and useful improvements in tracker-boards for 10 auto-pneumatic music playing instruments.

My object is to provide in such a device certain improved features of construction which shall embody the advantages of a metal tracker-board without the disadvantages thereof. It has been found by the use 15 of an all-metal tracker-board that, owing to the hardness of the material and the sharpness of the edges of the duct perforations, that the paper note sheet in traversing the same is shaved or abraded, with the result 20 that the particles thus removed tend to clog the hole or duct, or otherwise impair the internal mechanism. This disadvantage is entirely removed by my present improved 25 construction. Furthermore, this improved construction embodies all the advantages of an all-wood tracker-board.

In the drawings, Figure 1 is a perspective view of a portion of my improved tracker-board. Fig. 2 is a cross section thereof 30 intersecting one of the ducts.

1 represents the main body of the tracker-board formed of wood or some analogous material.

2 represents a metallic facing for the upper 35 portion of the body 1, over which facing the paper of the note sheet (not shown) travels. The central part of this facing 2 is cut away longitudinally, the ends being 40 preferably connected as at 2^a.

3—3 represent openings or holes in the upper part or ridge of the tracker-board, which communicate with the several ducts, one of the latter being shown at 4 in Fig. 2. 45 The body 1 is provided with an upwardly extending rib or projecting portion 1^a standing between the two side bars of the lining 2, and so as to lie substantially flush, or very slightly above, the upper surface of 50 said facing. The aforesaid holes 3—3 are formed in the material of the body 1, which, being relatively soft, will not shave or abrade the paper of the music sheet as it traverses the board, hence the tracker-board possesses that advantage character-

istic of the all-wood board. The metal facing 2 is so adapted to the upper edge of the board as to protect the same and preferably so as to reinforce the same, it being secured thereto in any desired manner, for 60 example, by means of the inturned clamping flanges 2^b—2^b. The upper surface of this metal facing may be polished to any desired degree to provide a suitable bearing over which the paper may travel. The edge 65 of the facing nearest the holes 3—3 is spaced apart from the holes 3—3 sufficiently far so that there is no danger of abrasion. Abrasion may be further guarded against by causing the projecting portion of the body 70 1 to stand slightly above the upper surface of the metal facing, as already indicated. The presence of the metal facing serves not only to protect the upper edge of the tracker-board from injury such as bruising, but also 75 may reinforce the same against checking or splitting. This composite construction, therefore, possesses, as I have indicated at the outset, the advantages of the all-metal board as well as the advantages of the all- 80 wood board, with none of the disadvantages of either.

In the preferred form, the facing in effect provides a metallic bearing along each side 85 of the row of holes 3—3, but spaced apart therefrom.

What I claim is:

1. A composite tracker-board having a main body of wood or analogous material, and having a metallic facing along its upper 90 edge, said facing having a longitudinal slot, the material of the body projecting into said slot and arranged substantially flush with the upper surface of the metallic facing, and a duct in said tracker-board having its 95 opening in that part of the material of the body projecting into said slot.

2. In a tracker-board, a main body of wood or analogous material, said main body having ducts therein and having duct openings arranged in a row therein, and a metallic facing along the upper portion of said body, said facing being spaced away from said row of duct openings and being arranged substantially flush with the material of said 100 main body adjacent to said openings.

3. In a tracker-board, a main body of non-abrasive material having ducts therein and having metallic bearing surfaces extending parallel with and on both sides of, 110

but spaced away from, said ducts, said metallic portions also forming reinforcing and protecting linings for said tracker-board.

4. In a tracker-board, a main body portion of wood or analogous and non-abrasive material having ducts therein and having a metallic bearing surface adjacent to, but spaced apart from, said ducts, said metallic portion forming a surface protecting element for said tracker-board.

5. In a tracker-board, a series of ducts,

the material of the tracker-board surrounding said ducts being relatively soft or non-abrasive, bearing surfaces on the face of said tracker-board adjacent to the material in which the duct passages are formed and spaced apart therefrom and being of relatively harder material.

ROBERT S. GOURLAY.
